UNITED STATES PATENT OFFICE.

ROBERT Q. WILSON, OF CENTERVILLE, IOWA, ASSIGNOR OF ONE-HALF TO WILLIAM ELLIS, OF CENTERVILLE, IOWA.

STREET-REGISTER FOR CARS.

1,114,324.

Specification of Letters Patent. Patented Oct. 20, 1914.

Application filed May 1, 1913. Serial No. 764,865.

To all whom it may concern:

Be it known that I, ROBERT Q. WILSON, a citizen of the United States, residing at Centerville, in the county of Appanoose and State of Iowa, have invented certain new and useful Improvements in Street-Registers for Cars, of which the following is a specification, reference being had therein to the accompanying drawing.

10 This invention relates to an attachment which is intended to be used in connection with a street car, and the principal object of the invention is to provide a device which may be used for indicating to the passengers 15 the name of the next street at which the car will stop.

Another object of the invention is to provide an improved means for operating the rollers which cause the ribbon to move.

20 Another object of the invention is to provide an improved means for reversing the travel of the ribbon.

With these and other objects in view, this invention consists of certain novel combinations, constructions, and arrangements of parts as will be hereinafter fully described and claimed.

In the accompanying drawings: Figure 1 is an end view of the device. Fig. 2 is a 30 front elevation of the device. Fig. 3 is a transverse view taken along the line 3—3 in Fig. 2. Fig. 4 is a view similar to Fig. 1 with certain of the gears removed. Fig. 5 is a view of the gearing shown in Fig. 1 and 35 looking from the top of the figure. Fig. 6 is a plan view of the frame forming a portion of this machine with the operating mechanism removed. Fig. 7 is a view of the latch which holds the shifting plate in an 40 adjusted position. Fig. 8 is a view of the drum upon which the operating cord of this device is wrapped. Fig. 9 is a view of the drum looking at the opposite face of the drum shown in Fig. 8. Fig. 10 is a view of 45 the spring compressing arm forming a portion of this machine. Fig. 11 is a side elevation of the arm forming part of the shifting mechanism. Fig. 12 is an elevation of the device which operates the trigger for releasing the shifting plate. Fig. 13 is a front 50 view of the housing in which the mechanism is mounted.

This invention comprises a frame having the end plates 10 and 11 connected by the rods 12 and 13, the rods 12 carrying rollers 55 12' over which the curtain passes. Drums 14 and 15 are rotatably mounted between the plates 10 and 11 and each drum is provided adjacent one end of its axle 15' with a gear wheel 16 which is relatively small and 60 rigidly secured to the axle. Larger gear wheels 17 are loosely mounted upon the axles and engage the small gear wheels 18 extending from the larger gear wheels 19 meshing with the gear wheels 16'. It will 65 thus be seen that by turning the gear wheels 16 the rotary motion is transmitted through the small gear wheels 16' to the larger gear and wheels 19 through the small gear wheels 18 to the large wheels 17. The gears are of 70 such size that when the curtain is unwound from one drum and wound upon the other the gears 17 will each make a one fourth revolution.

A bracket 21 extends from the plate 11 75 and carries the bell crank levers 22 and 23 which are pivotally mounted by the pin 33 and connected with the gear wheels 17 by the rods 24 and 25 respectively. The arm 26 of the bell crank lever 22 is longer than the 80 arm 27 of the lever 23 so that when the shifting plate is in one position the stop member 76 will strike the arm 27, but when in the other position it will clear the arm 27 and strike the pin 76' on the arm 26. As the 85 machine is operated the arms 26 and 27 are gradually advanced so as to shorten the stroke of the ratchet member so as to compensate for the accumulation of web.

A plate 28 is slidably connected with the 90 end plate 11 by means of pins 30 upon which the gears 31 and 32 are mounted. A gear wheel 34 is mounted upon a stub shaft 33 and meshes with the gear wheel 31. By shifting the plate 28 the gear 31 may 95 be brought into mesh with the gear 16 rigidly mounted upon the axle of the drum 15, or the gear 32 may be brought into mesh with the gear wheel 16 rigidly mounted upon the axle of the drum 14. A gear 100 wheel 37 meshes with the gear wheel 16 of the drum 15 and also meshes with a gear wheel 38 mounted upon the outer end of the threaded shaft 39. By this construction the

shaft 39 may be caused to rotate according to the direction in which the drum 15 is rotated.

A shaft 40 is positioned between the plates 10 and 11 and held in place by the screws 41 and carries springs 42 and 43 positioned upon opposite sides of an arm 44 slidably mounted upon the shaft 40 and provided with a threaded opening through which the threaded shaft 39 passes. This arm 44 is also provided with fingered plates 44' through which a shaft 45 passes upon which nuts 46 and 47 are adjustably mounted to form abutments to cause the shaft 45 to be moved with the arm 44. A latch 48 is slidably connected with the plate 28 by means of the guide 49 and adapted to selectively engage the notches 50 and 51 formed in the cross bar 52 of the end plate 11, thereby holding the plate in an adjusted position. When the latch is in the notch 50 the gear 32 will be in mesh with the gear 16 of the drum 14 and when the latch is in the notch 51 the gear 31 will be in mesh with the gear 16 of the drum 15. A spring 53 is connected with the latch and plate 28 to normally hold the latch in engagement with the bar 52, thus preventing any danger of the latch slipping out of the notch. The upper end portion of the latch is bent to form an extension 54 extending across a shaft 55 pivotally mounted in bearings 56 and carrying cams 57 and 58. A lever 59 extends from the shaft 55 and is provided with an opening 60 through which a pin 61 passes to rock the shaft 55, thus reversing the position of the cams 57 and 58 and permitting the latch to drop from the higher cam on to the lower one. When the gear 38 has been rotated a sufficient amount to bring the arm 44 into engagement with the nut 46 or 47 the lever 59 will be rocked to rotate the shaft 55, thus raising the latch out of engagement with the notch in the bar 52 and permitting the plate 28 to be shifted to a desired position, thus drawing the latch from the higher cam and permitting the spring 53 to draw it downwardly onto the lower cam and into the second notch.

An arm 62 extends from the shaft 40 and carries a rod 63 upon which a second arm 64 is adjustably mounted. The arm 62 is engaged by the spring 43 and the arm 64 is engaged by the spring 42, thus causing the rod 63 to be moved in whatever direction the arm 44 is traveling. A pin 65 extends from the arm 62 and engages an arm 66 extending from a shaft 67 rotatably mounted in bearings 68. A finger 69 extends from the shaft 67 and is positioned between the lugs 70 carried by the plate 28. When the arm 44 is moved toward the arm 64 the spring 42 will be compressed until the arm strikes the nut

46. The rod 45 will then be moved to release the latch 48 which will permit the spring 42 to expand, thus moving the rod 63 to rock the shaft 67 and shift the plate 28. It is, of course, obvious that if the shaft 39 is rotated in the opposite direction that the plate 28 will be shifted in an opposite direction.

A drum 71 is rotatably mounted upon the shaft 33 extending from the plate 28 and carries pawls 72 which engage a gear wheel 73 rigidly mounted upon the shaft 33. This drum 71 carries a line 74 which operates the device and is provided with a spring 75 which holds the drum in a normal position. This drum is loosely mounted so that the gear wheel 34 may be intermittently rotated. A pin 76 extends from the drum 71 and is adapted to engage the lever 26 or 27 according to the position of the plate 28.

When this device is in use, the gearing is mounted in a suitable housing such as shown in Fig. 13, which housing is provided with an opening through which the ribbon may be seen. The line 74 passes through an opening formed in the housing and is of such length that it may be easily reached by the motorman or conductor to operate the device. As soon as a street is passed the motorman or conductor takes hold of the line and by pulling the same rotates the drum 71. This causes the gearing 34 to be rotated, and rotary motion will be transmitted from the gearing 34 to one of the gears 16 which are mounted upon the axles of the drums 14 and 15. This will rotate the drum to wind the ribbon and bring a new name in front of the opening and at the same time will transmit rotary motion through the small gears 16' mounted upon the axles to the large gears 19 which mesh with them. The small gears 18 carried by the large gears 19 will transmit the rotary motion to the large gears 17 loosely mounted upon the axle and connected to the bell-crank levers by the rods leading from these large gears to the levers. The free ends of these levers form stops which alternately engage the pin 76 to limit the rotation of the drum and these levers are moved by the loosely mounted gears to gradually lessen the stroke of the actuating drum 71 to compensate for the increased size of the take-up roll. As soon as the line is released, the spring 75 returns the drum to its normal position and the device is then ready for a second operation. This line is pulled every time a street corner is passed, thus moving the ribbon to indicate to the passengers within the car, the name of the next street. As soon as the car has reached the end of the route, the shifting mechanism, as already described, will operate automatically to shift the direction of the ribbon travel,

thus causing the names of the streets to appear in the opposite order from the order in which they were when the car was traveling in the opposite direction. As the loosely mounted gear rotates, it turns the bell crank levers, thus bringing the proper lever to be engaged by the stop pin 76.

A machine has, therefore, been provided which will operate very efficiently and 10 which will change the travel of the ribbon when the car has reached the end of the route.

What is claimed is:

1. A machine of the character described 15 comprising a frame, winding drums rotatably connected with said frame, a shifting plate pivotally connected with said frame, and provided with means for transmitting rotary movement to a selected one of said 20 drums, shifting means for said plate carried by said frame, springs for operating said shifting means, a latch for holding said plate in an adjusted position, and means for placing said springs under a tension and 25 releasing said latch to permit said springs to expand and to shift said plate.

2. A machine of the character described comprising a frame, winding drums rotatably connected with said frame, a shifting 0 plate pivotally connected with said frame, operating means for said drums carried by said plate, a rod forming part of said frame, an arm slidably mounted upon said rod, springs carried by said rod and engaging 5 said arm, a latch for said plate, a rocker shaft connected with said frame and engaging said plate, operating means for said rocker shaft engaged by said springs, operating means for said latch positioned within 0 the line of travel of said arm, and means for shifting said arm to place said springs under a tension, and actuate the operating means of said latch to release the latch and 5 permit said springs to expand and shift said plate.

3. A machine of the character described comprising a frame, winding drums rotatably connected with said frame, a shifting plate pivotally connected with said frame 0 and provided with means for transmitting rotary movement to a selected one of said drums, a latch carried by said frame and engaging said shifting plate to hold the

same in an adjusted position, a rod forming part of said frame, a rocker shaft carried 55 by said frame and engaging said shifting plate whereby said plate will move with said shaft, springs mounted upon said rod, operating means for said rocker shaft mounted upon said rod and engaged by said springs, a threaded shaft carried by said frame, an arm threaded upon said shaft and engaging said springs, a cam shaft carried by said frame for operating said latch, and a rod for actuating said cam shaft slidably 60 connected with said frame and provided with abutments adapted to be engaged by said arm whereby the travel of said arm will press one of said springs and after said spring is pressed engage one of said abutments to shift said slideable rod and rotate said cam shaft to release said latch and permit said spring to expand and turn said rocker shaft to shift said shifting plate. 65

4. A machine of the character described 70 comprising a frame, a shifting plate slidably connected with said frame and provided with means for transmitting rotary movement to a selected one of said drums, a 75 rocker shaft carried by said frame and engaging said shifting plate, a latch carried by said shifting plate and engaging said frame for holding said shifting plate in an adjusted position, a cam shaft engaging said latch, a sliding rod carried by said 80 frame and connected with said cam shaft, a rod forming part of said frame, an arm extending from said rod and engaging said rocker shaft to rotate the same, a threaded shaft carried by said frame, an arm threaded upon said shaft and extending across said rod, a spring mounted upon said rod between said arms, means carried by the arm mounted upon said threaded shaft for 85 engaging said sliding rod, whereby the movement of said last mentioned arm will move said sliding rod to rotate said cam shaft and release said latch to permit said 90 spring to expand and rock said rocker shaft to shift said shifting plate. 95

In testimony whereof I hereunto affix my signature in presence of two witnesses.
